UNITED STATES PATENT OFFICE.

EDWIN ROBERT HOUGH AND LAURENCE HARRISON, OF LONDON, ENGLAND.

ELECTRIC-LIGHT FITTING OR BRACKET.

1,211,847.

Specification of Letters Patent.

Patented Jan. 9, 1917.

Application filed February 14, 1916. Serial No. 78,247.

To all whom it may concern:

Be it known that we, EDWIN ROBERT HOUGH and LAURENCE HARRISON, subjects of the King of Great Britain, and both residing at Sutherland House, 3 Lloyd's avenue, London, England, have invented new and useful Improvements in Electric-Light Fittings or Brackets, of which the following is a specification.

10 Our invention relates to electric-light fittings or brackets of the kind wherein a cap or dome carrying the lamp holder is designed to have inserted into it a ring for supporting a well-glass globe or the like, and frequently provided with a guard the said ring being tightened against a packing in the cap or dome to render the fitting water-tight.

15 In the specification of former British patent granted to E. R. Hough, No. 2048 of 1914 an arrangement is described wherein pins on the inside of the cap engaged with inclined surfaces on the exterior of the ring, this construction, however, was objectionable in that sufficient adjustment of the ring within the cap to accommodate well-glasses having supporting flanges of varying thickness could only be obtained by making the ring unnecessarily deep.

20 According to our present invention the ring which carries the globe (with or without a guard) is only made of such depth as will give it the necessary strength and is provided with pins or projections designed to engage with inclined slots of considerable length formed spirally on the inner surface of the cap or dome, whereby a relatively considerable degree of movement of the said ring into the cap or dome is permitted so that sufficient adjustment is provided for to enable well-glasses or the like having flanges of varying thickness, being utilized in one and the same fitting.

25 To enable the invention to be fully understood we will describe it by reference to the accompanying drawings, in which:

30 Figure 1 is a perspective view of an electric-light fitting having our improvements applied thereto and shown in conjunction with a guard. Fig. 2 is a perspective view partly in section of the cap. Fig. 3 is a perspective view of the ring with the guard attached. Fig. 4 is a sectional elevation of the cap illustrating a modification, and Fig.

5 is an underside view thereof. Fig. 1 is drawn to a smaller scale than the remaining figures of the drawing.

Referring first to the construction of fitting shown in Figs. 1 to 3, *a* indicates the guard, *b* the annular end or ring thereof and *c* the lugs or pins which project from the periphery of the said ring *b*. *d* indicates the cap or dome, *e* the annular rim thereof and *f* spiral slots which are equal in number to the pins *c* and similarly positioned and are formed on the inner face of the said rim *e* and extend from notches *g* on the underface of the said rim in a direction inclining away from the said underface. The guard *a* is secured to the cap or dome *d* by passing the ring *b* into the rim *e* in such a position that the radial lugs *c* on the former pass through the notches *g* and into the spiral slots *f* and then turning the said ring *b* in the proper direction to cause the lugs *c* to travel along the said slot *f* whereby the flange of a globe resting upon the said ring will be pressed against the head of the cap or a packing ring thereon. As has been above explained, the slots *f* are made of such length that a considerable degree of adjustment is obtained which is sufficient to enable glass globes or well-glasses having flanges of varying thickness being utilized in one and the same fitting. As before stated where the guard is not required the ring *b* simply serves for supporting the globe in the cap or dome. *h* is a screw-pin which serves as a locking means for preventing the unauthorized removal of the globe or globe and guard, the said pin *h* passing through a screw threaded hole *i* in the rim *e* of the cap or dome and having a point *j* which can be caused to press against the outer face of the ring *b* when the latter has been adjusted in position in the rim. This locking pin is furnished with a head *k* of triangular shape which is inclosed in a socket *l* upon the outer periphery of the rim *e*. The outer end of the said socket *l* is furnished with a cap *m* provided with a triangular opening *n*, seen in Fig. 1, for preventing the introduction of anything other than a triangularly shaped key which fits the screw head into the socket for unlocking the ring.

35 40 45 50 55 60 65 70 75 80 85 90 95 100 105 In Figs. 4 and 5 we have illustrated a modified form of auxiliary locking means.

In this construction the ring b^1 of the holder is furnished with teeth o on its outer periphery and in conjunction with the said toothed periphery there is provided a toothed disk p which is eccentrically keyed on, or formed integral with, the pin q . This pin q has a triangular shank r which extends into a socket s on the underside of the rim e^1 this socket s being similar to the socket l described with reference to Figs. 1 to 3. With this construction the toothed eccentric p can, by means of a key, inserted into the socket s so as to engage the shank r of the pivot pin q , be turned out of engagement with the toothed periphery o of the ring b^1 thus permitting the latter to be adjusted in the rim e^1 ; when the ring b^1 is adjusted, the toothed eccentric p can be turned so that its teeth can engage with the teeth o of the ring b^1 and thus lock the latter in position, the arrangement being such that any attempt to turn the ring b^1 , so as to remove it from the rim e^1 tends to tighten the grip of the eccentric p upon the ring. To prevent the insertion of a wire or like device between the teeth of the ring b^1 and the inner periphery of the rim e^1 so as to disengage the toothed eccentric p from the ring b^1 , the latter may be provided with an outwardly extending flange on the lower surface which extends beneath the lower face of the flange e^1 . If desired the teeth o can be dispensed with, the teeth of the eccentric engaging with the periphery of the ring

which may be left rough as it is taken from the mold.

As will be understood the auxiliary means of locking as above described are given by way of example only, as any other convenient means for the purpose may be made use of.

Claims:

1. An electric light fitting or bracket comprising a cap provided with an annular rim having spiral grooves formed in its inner surface and extending from the lower edge of said rim to within a short distance of the cap, a supporting ring for clamping the annular rim of a well-glass against said cap, mounted in said rim and provided on its periphery with lugs which engage said grooves, and means for locking said ring in said rim.

2. An electric light fitting or bracket comprising a cap provided with an annular rim having spiral grooves formed in its inner surface, a supporting ring for clamping the annular rim of a well-glass against said cap, mounted in said rim and provided with lugs which engage said grooves, teeth formed in the periphery of said ring, and a toothed eccentric adapted to engage the teeth of said ring for locking the ring in the rim.

EDWIN ROBERT HOUGH.
LAURENCE HARRISON.
